CLAIM

The ornamental design for a material stacking bin for
use with a pallet, as shown.

DESCRIPTION

FIG. 1 is a side perspective view of a material stacking
bin for use with a pallet showing my new design;

FIG. 2 is a bottom perspective view thereof;

FIG. 3 is a perspective view thereof of the side oppo-
site to that shown in FIG. 1; and

FIG. 4 is a top perspective view thereof.

FIG 2

FIG 1

FIG. 4

FIG. 3
